CLAIM

The ornamental design for a baseball cap with decorative bill, as shown and described.

DESCRIPTION

FIG. 1 is a top view of the baseball cap with decorative bill of the present invention;

FIG. 2 is a bottom view of the baseball cap with decorative bill of FIG. 1;

FIG. 3 is a left side view of the baseball cap with decorative bill of FIG. 1;

FIG. 4 is a right side view of the baseball cap with decorative bill of FIG. 1; and,

FIG. 5 is a front view of the baseball cap with decorative bill of FIG. 1.

The broken line showing of crown of the baseball cap in all views is for illustrative purposes only and forms no part of the claimed design.
